SLUDGE PUMPING ASSEMBLY

Carl Roy Johnson, Chicago, Ill., assignor to Yeomans Brothers Company, Melrose Park, Ill., a corporation of Delaware

Application November 25, 1953, Serial No. 394,264

2 Claims. (Cl. 103—45)

The present invention is directed to an improved apparatus for handling materials such as sludge and industrial wastes of different natures which are difficult to pump efficiently.

Numerous different arrangements are currently in use for the purpose of pumping sludge suspensions at various concentrations. Each has its own advantages and its disadvantages. From the standpoint of operating efficiency, one of the best of these arrangements is a pneumatic ejector of the type which consists of a closed receiver provided with check valves on the inlet and in the discharge lines, a control valve mounted on the receiver and a pair of open bells suspended in the receiver and movable in response to the liquid level in the receiver to operate the control valve. The control valve, in turn, actuates a piston valve which operates to introduce and to terminate the flow of compressed air into the receiver during the discharge cycle.

This type of pneumatic ejector is very efficient in operation and requires little maintenance. However, the unit is expensive to install and is somewhat expensive to operate because of the necessity of providing high pressure air. Moreover, ejectors of this type operate by a gravity feed and must be located so that the inlet to the ejector is lower than the discharge point for the sludge being received. Normally, this necessitates providing a special chamber or other enclosing structure located below the floor level of the building in which the ejector unit is installed. Such enclosures add materially to the cost of the installation and makes the unit relatively inaccessible for purposes of lubrication and whatever maintenance that may be required.

In strictly mechanical systems for handling sludges, it is common to employ positive displacement sludge pumps of the plunger type in which the fluid is pumped by the reciprocating action of a piston type plunger. Normally, the pistons of such pumps are driven by means of an eccentric connected to a positively driven shaft. The drive means and the eccentric are coupled together by means of a shear pin which provides some degree of protection against excessive stresses in the drive mechanism. Pumps of this type are essentially constant speed mechanisms, with only the stroke of the plunger being capable of adjustment and that to only a limited extent. Further, when the plunger displacement is to be changed it requires shutting down the pump and realigning the eccentric with respect to the driven shaft. This procedure is, of course, time consuming and incapable of fine adjustment of the stroke of the plunger except by continuous trial and error.

An even more serious objection to the eccentric drive, plunger type sludge pump arises from the fact that the motion of the plunger is not strictly an up and down motion but has a lateral component which creates excessive wear on the packing of the cylinder. Additionally, these pumps are subject to considerable vibration during use, as a result of the reciprocation of the plunger, and

2

this requires heavy construction, expensive pump mountings, original cost and maintenance are high, and the operation is incapable of continuous or rapid adjustment.

5 Thus, both of the most commonly used types of sludge pumps do not completely satisfy the requirements of the art, and there is a continuing need for an improved pump mechanism for handling sludge and sludge type materials which is efficient in operation and inexpensive to maintain and to install. The provision of such a pump mechanism is the principal object of the present invention.

Another object of the invention is to provide an improved pump mechanism particularly adaptable to handling sludge and sludge type products under such conditions that the rate of discharge of the pump can be readily and continuously varied during the operation of the pump, without shutting down the unit.

Still another object of the invention is to provide a drive mechanism for sludge pumps which eliminates the 20 numerous gear assemblies of existing drive units and thereby eliminates the objectionable noise and relatively high expense of such gear assemblies.

An illustrative embodiment of the invention is illustrated in the accompanying drawings where:

25 Figure 1 is a somewhat schematic view in elevation of a complete pump mechanism in accordance with the invention, and

30 Figure 2 is an enlarged view in elevation and partly in cross section illustrating certain natures of the pump mechanism shown more fully in Figure 1.

The pump mechanism illustrated in Figures 1 and 2 includes a pump cylinder or receiver generally indicated at numeral 10 in which a plunger 11 is arranged to reciprocate. The cylinder 10 is relieved to accommodate a stuffing box gland 12 and a plurality of packing rings 13 (Figure 2).

The sludge or other material to be pumped is introduced into the mechanism through an inlet line 14, the flow through the line 14 being governed by a ball valve 40 element 16 arranged to be seated on a removable valve seat ring 17. On the upstroke of the plunger the sludge entering the inlet line 14 unseats the ball element 16 and passes into the pumping chamber 18 where on the downstroke it is acted upon by the reciprocatory movement of the plunger 11. The sludge then under pressure is forced through an outlet line 19, and unseats the outlet valve member 20 which normally rests in seated relation on a removable valve seat ring 21. The inflow valve is, of course, closed at this time. The pumped sludge is conducted away from the pump mechanism through an outlet line 22.

The plunger, in the illustrated mechanism, has a generally hollow interior and is provided with a centrally disposed cylindrical shaft 23. The upper end of the 55 shaft 23 is received within a fluid tight casing 24 and has a piston head 27 arranged to move in the casing 24 in response to fluid pressure in the casing 24. In the position of the mechanism shown in Figure 2, the plunger 11 is at the bottom of its stroke and is arranged to move upwardly upon the introduction of a pressure fluid such as oil into an inlet conduit 28 which communicates with the casing 24. As the hydraulic fluid under pressure is introduced into the conduit 28, it acts against the piston head 27 on the shaft 23 and forces the piston and hence the plunger 11 upwardly.

A second conduit 29 is connected to the casing 24 at a point above the limit of travel of the piston head 27, and like the conduit 28 is designed to admit hydraulic fluid to the casing 24 or to convey fluid from that casing 70 depending on the direction of movement of the piston head 27. Thus, as the plunger reaches the upper end

of its stroke, hydraulic fluid is introduced into the conduit 29 and simultaneously drained from the conduit 28 so that the fluid acting from the top of the piston head 27 causes the plunger to reverse its direction and commence its downward stroke. Similarly, in the upward stroke, when fluid is being introduced into the conduit 28, the fluid remaining in the casing 24 is being drained through the conduit 29 by a control system subsequently to be described. The casing 24 and the piston head 27 thereby provide a hydraulic ram mechanism for controlling the reciprocating movement of the plunger 11.

To obtain the fullest realization of the advantages of the invention, it is important that the hydraulic ram mechanism for actuating the plunger shall include means whereby the length of the stroke of the ram (and the pump plunger 11) can be varied. This is accomplished by a hydraulic control system which is illustrated in Figure 1 of the drawings. This system includes a pump 31 having a discharge line 32 and an inlet line 33. The hydraulic fluid is constantly supplied into the inlet line 33 from a reservoir 34.

A spring loaded relief valve 36 is located in the discharge line 32 for the purpose of preventing the pressure in the line from reaching too high a value. If the pressure is below a certain predetermined safe value, the fluid passes directly through the relief valve 36, but if the pressure exceeds the predetermined value, at least some of the fluid is shunted back into the reservoir 34 through a line 37. The discharge line 32 is in continuous fluid communication, by way of line 38, with an inlet 39 of a reversing valve 40, and also with a port 41 on a two-way pilot valve 42.

The reversing valve 40 may consist of a casing in which a sliding plunger with ports provided therein is free to slide in response to changes in fluid pressure at opposite ends of the slide. In the type of valve shown in the drawings, the reversing valve has a pair of oppositely spaced ports 43 and 44 which receive the hydraulic fluid to act against one or the other end of the slide 40 contained in the casing, and a pair of outlet ports 46 and 47 which alternately communicate with the inlet port 39 through the ports in the slide, depending upon the position of the slide in the reversing valve casing. Another outlet or exhaust port 48 is provided along with a conduit 49 to drain fluid from whichever port 46 or 47 is not being supplied with the pressure fluid back into the reservoir 34.

As shown in Figure 1, the port 46 of the reversing valve 40 is connected to the line 29 of the hydraulic ram assembly and the port 47 is connected to the line 28. Hence, by operation of the reversing valve, fluid is alternately introduced under pressure into the line 28 from the port 47 to move the plunger 11 upwardly, and in the next half cycle, the pressure fluid is introduced through the line 29 into the port 46 to reverse the movement of the plunger 11.

The operation of the reversing valve 40 is controlled by the pilot valve 42 which determines into which end of the valve 40 the hydraulic fluid is introduced. The pilot valve 42 includes four ports, the first of which, 41, is in constant fluid communication with the pump 31. A second port 51 and an associated conduit 52 serve to drain the hydraulic fluid from the pilot valve back into the reservoir 34 as indicated by the arrows. A pair of ports 53 and 54 are alternately connected through the valve to the inlet port 41 and function to introduce the hydraulic fluid alternately into ports 43 or 44 of the reversing valve 40.

The rate of deceleration or acceleration at the ends of the plunger stroke are very conveniently controlled by providing a pair of adjustable speed control throttling valves 56 and 57 in the lines 58 and 59 which connect the ports 54 and 53 with the ports 44 and 43, respectively, to regulate the amount of hydraulic fluid entering the reversing valve 40 from the pilot valve 42.

The speed of the plunger is governed by the setting on a bypass valve 61 located in the line 62 which connects the discharge line 32 to the reservoir 34. The position of the valve 61 is adjustable to vary the amount of fluid available to actuate the hydraulic control system by returning continuously predetermined amounts of the fluid back to the reservoir. By this means a uniform output pump 31 can be used to drive the sludge pump at varying speeds.

The pilot valve 42 is operated by a V-shaped control member 63 which is arranged to be engaged by an operating dog 64 carried on a shaft 66. The movement of the control member 63 from one position to its other position changes the flow of fluid through the pilot valve 42 in the manner previously described, to thereby control the operation of the reversing valve 40.

In the drawings, the plunger 11 is shown in its lowermost position. As the plunger moves into this position, the pilot valve 42 is moved to cause the oil or other hydraulic fluid to pass from the port 41 into the port 54, through the valve 56, and into the port 44 of the reversing valve 40. When this happens, the pressure at the end of the slide contained in the reversing valve 40 causes the slide to move from right to left. As the slide shifts, it establishes communication between the inlet line 38 and the port 47 to introduce fluid under pressure into the lower end of the hydraulic ram assembly and thereby force the piston head 27 upwardly. At the same time the position of the pilot valve 42 is such that the port 53 is open to the drain port 51 so that fluid from the opposite end of the reversing valve 40, at the port 43, can drain back into the reservoir 34 through the conduit 52. In this position, the drain port 48 of the reversing valve is open to port 46 of the same valve thereby permitting the hydraulic fluid from the upper part of the hydraulic ram to be drained through the line 29 and the line 49 back into the reservoir 34.

As the plunger 11 approaches the upper end of its stroke, the dog 64 engages the control member 63 and moves it to the dotted line position shown in Figure 1. In this position of the valve, the port 41 is in communication with port 53 so that fluid under pressure is introduced through the valve 57 into the port 43 and into the reversing valve 40. The slide of the reversing valve 40 then shifts to the right in response to this change in pressure and the inlet line 38 is then connected through the slide with the port 46 and the line 29. At the same time, the drain port 48 is in fluid communication with the port 47 so that as the hydraulic fluid exerts its pressure on the top of the piston head 27, the hydraulic fluid at the base of the hydraulic ram is drained through the line 28 and the line 49 back into the reservoir 34. Similarly, in this position the port 54 of the pilot valve 42 is connected to the drain port 51 so that hydraulic fluid is drained from the port 44 of the reversing valve assembly. This completes the cycle of operation.

The present invention provides a very convenient means for adjusting both the stroke and speed of plunger-type pumps in a manner not previously possible with conventional sludge pumps. One of the important advantages of the assembly is the fact that the plunger is operated in a strictly up and down motion without substantial side thrust on the plunger elements which would create undue wear on the packing. This absence of lateral thrust caused by the plunger movement is also responsible for the substantial decrease in mechanical vibration accomplished by pumps of the present invention.

The capability of the present assembly to be accurately adjusted over a wide speed range makes it preferable to other types of pumps, even those employing an expensive variable speed drive because the means for varying the speed in the present assembly is considerably simpler and less capable of mechanical damage.

It will be evident that various modifications can be made to the structure of the above-described assembly

without departing from the scope of the present invention.

I claim:

1. A sludge pumping system comprising a receiver including an inlet, an outlet, and a plunger slidable within said receiver to effect an intake of material through said inlet and a discharge of such material through said outlet, a ram of the double acting type including a cylinder, a piston slidable within said cylinder, and a piston rod extending from said cylinder and inter-connected with said plunger, a constant delivery fluid pump, a reservoir supplying fluid to said pump, and means for adjustably controlling the operation of said plunger including a pressure relief valve, a by-pass valve, a reversing valve, a pilot valve, a pair of flow regulating valves, and means associated with said plunger for actuating said pilot valve and for controlling the length of stroke of said plunger, said reversing valve having individual communication with said pump, said reservoir, and with each of the ends of said piston whereby a first pressure fluid flow may be alternately directed from said pump through said reversing valve to one end and then to the other end of said piston and whereby a simultaneous withdrawal of pressure fluid may be afforded from the opposing end of said piston through said reversing valve to said reservoir, said by-pass valve and said pressure relief valve being intermediate of said pump and said reversing valve whereby the speed of the stroke of said plunger may be controlled and whereby overload protection may be secured, said pilot valve having individual communication with said pump, said reservoir, and with each of the ends of said reversing valve whereby, through cooperation of said pilot valve actuating means, a second pressure fluid flow is alternately directed from said pump through said pilot valve to one end and then to the other end of said reversing valve and a simultaneous withdrawal of pressure fluid is afforded from the opposing end of said reversing valve through said pilot valve to said reservoir, said second pressure fluid flow and said simultaneous withdrawal of pressure fluid from said reversing valve effecting reciprocation of said plunger by causing said first pressure fluid flow to be alternately directed to one end and then the other of said piston and by affording simultaneous withdrawal of pressure fluid from the opposing end of said piston, said second pressure fluid flow and said withdrawal of pressure fluid between said pilot valve and said reversing valve each being through said flow regulating valves for cushioning the ends of the stroke of said plunger by controlling the acceleration and deceleration thereof.

2. A motor means including a ram of the double acting type, a pressure source, and means for controlling the operation of said ram, said ram comprising a cylinder,

a piston slidable within said cylinder, and a piston rod extending from said cylinder, said control means comprising a by-pass valve, a pressure relief valve, a reversing valve, a pilot valve, a pair of flow regulation valves, and means associated with said piston rod for actuating said pilot valve and for controlling the length of the stroke of said piston, said reversing valve having individual communication with said pressure source, said reservoir, and with each of the ends of said piston whereby a first pressure fluid flow may be alternately directed from said pressure source through said reversing valve to one end and then to the other end of said piston and whereby a simultaneous withdrawal of pressure fluid may be afforded from the opposing end of said piston through said reversing valve to said reservoir, said by-pass valve and said pressure relief valve being intermediate of said pressure source and said reversing valve whereby the speed of the stroke of said piston may be controlled and whereby overload protection may be secured, said pilot valve having individual communication with said pressure source, said reservoir, and with each of the ends of said reversing valve, whereby, through cooperation of said pilot valve actuating means, a second pressure fluid flow is alternately directed from said pressure source through said pilot valve to one end and then to the other end of said reversing valve and a simultaneous withdrawal of pressure fluid is afforded from the opposing end of said reversing valve through said pilot valve to said reservoir, said second pressure fluid flow and said simultaneous withdrawal of pressure fluid from said reversing valve effecting reciprocation of said piston by causing said first pressure fluid flow to be alternately directed to one end and then to the other end of said piston and by affording simultaneous withdrawal of pressure fluid from the opposing end of said piston, said second pressure fluid flow and said withdrawal of pressure fluid between said pilot valve and said reversing valve each being through said flow regulating valves for cushioning the ends of the stroke of said piston by controlling the acceleration and deceleration thereof.

UNITED STATES PATENT OFFICE
CERTIFICATE OF CORRECTION

Patent No. 2,836,122

May 27, 1958

Carl Roy Johnson

It is hereby certified that error appears in the printed specification of the above numbered patent requiring correction and that the said Letter Patent should read as corrected below.

Column 4, line 16, after "reversing valve 40." insert the following paragraph:

The shaft 66 in turn is secured to the inside of the hollow plunger 11 as best illustrated in Figure 2 of the drawings. The actuating mechanism shown in the drawings is a simple example of the types of mechanisms which can be employed to accomplish the same purpose. The mechanism can be replaced, for example, by a pair of limit switches which are actuated by the movement of the plunger and which can be used to operate a solenoid to shift the control member 63 from one position to the other. Numerous other mechanisms for accomplishing this function will suggest themselves to those skilled in the art. The particular actuating mechanism illustrated in the drawings has the advantage that the stroke of the plunger may be very simply adjusted merely by positioning the dog 64 at the desired location along the shaft 66.

Signed and sealed this 21st day of October 1958.
